 SPRING AND MOLDED CUSHION
 Kenneth P. Ross, 8336 Washburn Ave. S.,
 Minneapolis, Minn.
 Filed July 27, 1962, Ser. No. 212,957
 5 Claims. (Cl. 5—351)

This invention relates to a novel cushion for furniture items or the like, and more particularly to a cushion wherein a spring core is uniquely combined with a surrounding casing of a foam or sponge material in a unique manner whereby the resulting cushion possesses good resilient and elastic characteristics, affording a soft padding, yet is sufficiently sturdy so that it cannot be unduly compressed when bearing a normal load.

Another object of the invention is to provide a novel means giving positive station to all parts of the spring core to retain the spring core properly disposed with respect to its surrounding foam encasement, even after a long period of use of the cushion, to insure that the spring core will not be felt by the user.

Still a further object of the invention is to provide a novel cushion construction wherein the center portion of the cushion, although resilient, will possess less resiliency than the exterior portion of the cushion.

Various other objects and advantages of the invention will hereinafter become more fully apparent from the following description of the drawing, illustrating a presently preferred embodiment thereof, and wherein:

FIGURE 1 is a plan view, partly in section and partly broken away, showing a cushion constructed in accordance with the invention;

FIGURE 2 is a fragmentary cross sectional view thereof;

FIGURE 3 is an enlarged fragmentary transverse sectional view taken substantially along a plane as indicated by the line 3—3 of FIGURE 1, through a part of the cushion;

FIGURE 4 is a fragmentary sectional view taken substantially along the line 4—4 of FIGURE 3, and

FIGURE 5 is an enlarged fragmentary sectional view of a part of the structure shown in FIGURE 4.

Referring more specifically to the drawing, the cushion in its entirety and comprising the invention is designated generally 7 and is broadly composed of a spring core unit, designated generally 8, and a surrounding encasement 9 of a molded foam or sponge material.

The resilient core unit 8 includes a plurality of coiled springs 10, each of which is enclosed in a separate fabric casing 11. Each casing 11 includes a cylindrical side wall 12 and end walls 13 which are integrally joined to the ends of the cylindrical side wall. The coiled springs 10, each enclosed in its casing 11, are enclosed by an outer fabric casing 14 which fits snugly around the springs 10. Said outer casing 14 includes normally substantially parallel walls 15 between which the springs 10 are disposed with their axes perpendicular to said walls 15, and a surrounding wall 16 which is integrally connected to the marginal edges of the walls 15.

As best illustrated in FIGURE 3, the adjacently disposed springs 10 and the casings 11 thereof are connected to one another and to the walls 15 of the outer casing 14 by suitable connecting means, shown in the drawing as hog rings 17; however, other connecting means such as stitching may be utilized. The portions of the hog rings 17, which protrude from the exteriors of each of the walls 15, are connected to one another by cords 18 which combine with said hog rings 17, the outer casing 14 and the individual inner spring casings 11 to effectively tie the springs 10 together to prevent movement of said springs

2

relative to one another except in directions coinciding with the axes of said springs. The casings 11 and 14 are each composed of a wide or loose weave fabric, such as muslin.

The outer foam or sponge encasement 9 of the cushion 7 may be formed of any suitable material which is molded by pressure such as urethane or polyester foams. The material of which the encasement 9 is formed is molded under pressure in any conventional manner around the core unit 8. During the molding operation and before the material constituting the encasement 9 has set, said material will seep through the walls 15, as seen at 9' in FIGURE 3, and also through the end walls 13 which abut the inner sides of said walls 15. Additionally, as seen at 9' in FIGURES 3, 4 and 5, a part of the foam material will seep through the surrounding wall 16 and through the parts of the walls 12, which contact said wall 16. Accordingly, when the material forming the encasement 9 has set, said encasement will be effectively bonded to all parts of the fabric casing 14 and to each of the individual spring casings 11 to insure and effectively maintain a positive station for each of the springs 10.

The resilient core unit 8 possesses less resiliency and elasticity than the surrounding foam encasement 9 so that the cushion 7 will possess a desired degree of stiffness in an area disposed approximately midway between its opposite surfaces 19 and 20 and a greater degree of elasticity and resiliency, adjacent said surfaces 19 and 20.

It will be understood that the cushion 7 may be made in various sizes and shapes such as an individual seat cushion or of a size to provide a mattress.

Various modifications and changes are contemplated and may obviously be resorted to without departing from the function or scope of the invention as hereinafter defined by the appended claims.

I claim as my invention:

1. A cushion comprising a resilient core unit including a plurality of coiled springs, a fabric casing enclosing all of said springs, and a one piece outer encasement of a pressure molded foam material completely enclosing said fabric casing, said fabric casing being of a loose weave material and having parts of the pressure molded foam material embedded therein and bonded thereto.

2. A cushion as in claim 1, said core unit including individual fabric casings each enclosing one of said springs, said individual fabric casings being enclosed by said first mentioned fabric casing and each having wall portions in contact therewith and of a loose weave material in which parts of the foam material are embedded for anchoring each of the individual spring casings to said first mentioned casing and to said foam encasement.

3. A cushion as in claim 2, and means connecting the end convolutions of the adjacently disposed springs to one another, said means connecting the individual casings to one another and to said first mentioned casing and including portions embedded in said molded encasement.

4. A cushion as in claim 3, said connecting means comprising hog rings.

5. A cushion as in claim 4, and cords engaging through and connecting portions of said hog rings which are disposed externally of said first mentioned fabric casing.
